INVENTOR

BY *Joseph Pukel*
Marvin Remm
ATTORNEY

UNITED STATES PATENT OFFICE.

JOSEPH PUKEL, OF NEW YORK, N. Y.

SWIMMING DEVICE.

Application filed June 11, 1923. Serial No. 644,609.

To all whom it may concern:

Be it known that I, JOSEPH PUKEL, a citizen of United States, residing at New York, in the county of New York and State of New York, have invented certain new and useful Improvements in Swimming Devices, of which the following is a specification.

This invention relates to improvements in devices for accelerating the speed of a swimmer and has as its main object to provide means readily engageable with the lower limbs of a person whereby the propelling forward effect of limb motion is greatly augmented and the reverse or upward stroke of the limb in no wise retarded.

Another purpose is to produce a device that can be used without additional fatigue, and in which the apparatus used on one limb does not interfere with the other.

A further object is in the provision of an apparatus so light in weight as to be practically negligible and which is automatic in its operation of opening or closing in accordance with the motion imparted to it by the user.

These several aims are attained by the novel construction, combination and arrangement of parts hereafter described, claimed, and shown in the annexed drawing, forming part of this disclosure, and in which:—

Figure 1 is a view illustrating the application of embodiments of the invention, one being shown in open, operative position and the other as closed.

Figure 2 is a front elevational view of the device as extended.

Figure 3 is a transverse sectional view taken on line 3—3 of Figure 2.

The invention is composed of a thin flexible strip 5 of light strong material as wood, disposed against the ankle, at a point above the instep nearly to the knee and held securely in place by a strap 6 fastened to its upper end, passing around the leg and held in adjustment by a buckle or like fastening 7.

A similar strap 8 is fixed in a like manner at the lower end of the strip to pass around the ankle to which it is adjusted by the buckle 9.

Another strap 10 is attached at its respective ends to the strip and to the strap 8 at the front, the bight of the strap passing under the sole and is adjustably held by the buckle 11.

Fixed to the front of the strip 5, above the lower strap 8, is an angular bracket 12, its outstanding element 13 acting as a support for a bar 14.

At a point midway in the length of the strip is fastened a rigid shield 15 containing a ring 16 on which are pivotally engaged the inner perforated ends of a plurality of ribs 17 connected centrally of their length by pivoted stretcher rods 18, the converging ends of which are pivotally engaged by a runner 19 freely slidable on the bar 14.

In order to prevent the ribs from folding too closely inward a block 20 is interposed adjacently below the shield 15, this block having recesses 21 adapted to maintain the ribs at a slight angle outwardly.

At the outer ends of the ribs 17 are secured thin, paddle shaped metallic plates 22 and disposed over these plates and ribs is a textile fabric covering 23, having a hem 24 at its outer edge to reinforce and strengthen the same.

From the foregoing it will be seen that an impelling device, in some respects resembling an umbrella, has been disclosed and that the same will instantly expand or open upon pressure being exerted downwardly on the strip when the same is submerged in water.

It will be equally apparent that upon raising the strip, the ribs will automatically fold, so that no extra exertion is required in the forward stroke of the limb, but that the propelling effect of a rearward or downward stroke is greatly intensified and in proportion to the size of the device as expanded.

Having thus described my invention and set forth the manner of its construction, application and use, what I claim as new and desire to secure by Letters Patent, is:—

1. A swimming device comprising a strip of material and means associated therewith to secure the same to a person's lower limb above the foot, a bar fixed on said strip to extend at a spaced distance parallel therewith, a shield fixed to said strip above said bar, ribs pivoted within said shield, a runner on said bar, stretcher rods engaging said ribs with the runner, a covering over said ribs, and means for limiting the folding of said ribs against said bar.

2. A swimming device comprising a wooden strip, straps confining said strip at the bottom and top to a person's ankle,

another strap engaging said strip with the foot, a bar spacedly carried in advance and parallel with said strip, a shield above said bar, converging ribs pivoted in said shield, 5 a runner slideable on said bar, pivoted connections between each rib and said runner, a notched block on said bar limiting the

closing in of said ribs, plates extending laterally from the outer ends of said ribs, and a textile covering secured over said plates ¹⁰ and ribs.

In witness whereof I have affixed my signature.

JOSEPH PUKEL.
